Primary Examiner — Leanne Was-Englehart*Assistant Examiner* — Justin A Johnson(74) *Attorney, Agent, or Firm* — Olav M. Underdal; IDP Patent Services(57) **CLAIM**

The ornamental design for a training harness, as shown and described.

DESCRIPTION

FIG. 1 is a front right side perspective view of a training harness showing our new design;

FIG. 2 is a front perspective view thereof;

FIG. 3 is a rear perspective view thereof;

FIG. 4 is a rear right side perspective view thereof;

FIG. 5 is a rear left side perspective view thereof;

FIG. 6 is a top perspective view thereof; and,

FIG. 7 is a bottom perspective view thereof.

The broken lines show unclaimed portions of the training harness only and form no part of the claimed design.

1 Claim, 7 Drawing Sheets(56)
